UNITED STATES PATENT OFFICE.

FRANK KRON, OF KANSAS CITY, MISSOURI.

ICE-PICK HOLDER.

Application filed July 24, 1922. Serial No. 577,048.

To all whom it may concern:

Be it known that I, FRANK KRON, a citizen of the United States, residing at Kansas City, in the county of Jackson and State of Missouri, have invented a certain new and useful Improvement in Ice-Pick Holders, of which the following is a specification.

My invention relates to improvements in ice pick holders.

10 One of the objects of my invention is to provide a holder of the kind described which is simple, cheap to make, durable, not liable to get out of order, which will hold an ice pick in an easily accessible position and 15 without danger of injury to persons passing adjacent thereto.

A further object of my invention is the provision of a holder of the kind described formed from a single piece of sheet metal 20 made into a tube and provided with supporting legs having means for attachment to a suitable support.

My invention provides further novel features of construction hereinafter fully described and claimed.

In the accompanying drawing, which illustrates the preferred embodiment of my invention,

Fig. 1 is a perspective view of my improved ice pick holder shown attached to a support and having an ice pick mounted therein.

Fig. 2 is a rear elevation of the holder.

Fig. 3 is a vertical sectional view on the line 3—3 of Fig. 4.

Fig. 4 is a top view of the holder.

Fig. 5 is a cross section on the line 5—5 of Fig. 2.

Fig. 6 is a reduced plan view of the blank from which the holder is formed.

Similar reference characters designate similar parts in the different views.

The holder comprises preferably an upwardly flaring tube adapted to receive the stem of an ice pick and to support the handle of the latter in a position extending above the upper end of the tube, as shown in Fig. 1.

The tubular holder has one or more rearwardly extending legs having means for attachment to a suitable support.

In the preferred embodiment of my invention, I provide a blank, such as is shown in Fig. 6, comprising a sheet of suitable material, such as tin plate or sheet brass. The blank has a body portion 1 which is

formed into an upwardly flaring tube 2, which is adapted to receive therethrough the stem 3 of an ordinary ice pick, the handle 4 of which is adapted to rest in a protruding position, on the upper end of the tube 2.

From the longitudinal edges 5 and 6 of the blank 1 are provided lateral extensions 7, 8, 9 and 10 respectively. The extensions 7 and 8, after the tube has been formed, extend rearwardly side by side and are held together by means of a lip 11, provided on the extension 7 and which is folded over the upper edge of the extension 8. The extensions 7 and 8 at their rear ends are turned laterally in opposite directions to form feet 12 and 13, each of which has a hole 14 adapted to receive a securing device such as a nail 15.

The extensions 9 and 10, after the tube has been formed, extend rearwardly side by side and are held together by a lip 16 on the extension 9 which is folded over the lower edge of the extension 10. The rear ends of the extensions 9 and 10 are turned laterally to form feet 17 and 18, each of which is provided with a hole 14 adapted to receive a securing device, such as a nail 15.

The nails 15 may be driven into any suitable support such as an upright board 19, Fig. 1, so as to fasten the feet 12, 13, 17 and 18 flatwise against the board with the tube 2 disposed in an upright position.

As shown in Figs. 2 and 3, the longitudinal edge portions may be overlapped, to prevent liability of the point of the pick passing between the longitudinal edges when the pick is thrust into the tube 2.

I do not limit my invention to the structure shown and described, as many modifications, within the scope of the appended claims, may be made without departing from the spirit of my invention.

What I claim is:—

1. An ice pick holder comprising a sheet of suitable material formed into an upwardly flaring tubular body, the longitudinal edges of the sheet having respectively two rearwardly extending portions having at their rear ends respectively two oppositely extending lateral extensions having means for attachment to a suitable support, one of said portions having a lip folded over the other extension for holding the extensions together.

2. An ice pick holder comprising a sheet

- of suitable material formed into a tube having overlapped longitudinal edge portions, the longitudinal edges being provided respectively with two rearwardly extending portions disposed side by side, one of said portions having a lip folded over the other portion for holding them together, said portions having means for attachment to a suitable support.
3. An ice pick holder comprising a sheet of suitable material formed into a tube, the longitudinal edges of the sheet having respectively two rearwardly extending portions disposed side by side, one having a lip folded over the other for holding the portions together, said portions having means for attachment to a suitable support.
4. An ice pick holder comprising a sheet of suitable material formed into an upwardly flaring tube, each longitudinal edge 20 of the sheet having two rearwardly extending portions disposed respectively side by side with respect to the extensions from the other longitudinal edge, the rear ends of adjacent extensions being turned laterally re- 25 spectively in opposite directions and having means for attachment to a suitable support, one extension of each pair having a lip folded over the other extension of the pair for holding the extensions together. 30

In testimony whereof I have signed my name to this specification.

FRANK KRON.
